UNITED STATES PATENT OFFICE.

EUGENE O. MYERS, OF LOS ANGELES, CALIFORNIA.

TOOL FOR FACING VALVE SEATS.

Application filed October 21, 1920. Serial No. 418,471.

To all whom it may concern:

Be it known that I, EUGENE O. MYERS, a citizen of the United States, residing at Los Angeles, in the county of Los Angeles and

5 State of California, have invented new and useful Improvements in Tools for Facing Valve Seats, of which the following is a specification.

This invention relates to tools for facing 10 tapered valve seats, and an object thereof is to provide an improved valve seat facer that is durable in its construction, is simple, and provides a series of relatively separable elements that can be readily interchanged for

15 renewal.

Another object of the invention is to provide for the ready interchange of pilot stems of different sizes, so that a pilot stem may be employed of a size corresponding to that 20 of the valve stem relative to the particular valve seat that is to be faced. In this connection a further object is to provide means for efficiently centering the interchangeable pilot stems so that they will be truly aligned 25 with the valve stem guide aperture and with respect to the valve seat of the valve.

Another object is to provide an improved 30 valve seat facer in which a very desirable rigidity of construction and assembly of the parts is secured and to provide for the uniform advancement of a series of cutters or blades of the tool by the proper centering or guiding of the cutter expander and so mounting it as to eliminate play on the supporting shank and the threads.

Another object is to provide an improved body block with means for facilitating the effective clamping of the relatively removable cutting members.

40 A further object is to provide a valve seat facing tool embodying a series of blades arranged around an axis and offset relative to radii struck from the axis to prevent chatter of the tool and to hold the tool to the work.

45 A further object is to provide a tool of the above character in which the adjustable blades will be firmly held against tipping laterally or longitudinally and will have a substantial bearing surface to obviate the 50 possibility of their being displaced and to insure their cutting a true surface.

55 With the foregoing objects in view and such other objects and advantages as may later appear, the invention consists substantially of the construction, the combination, and the details and arrangements of the parts

hereinafter set forth and claimed. A preferred embodiment of the invention is illustrated in the accompanying drawings, in which:

60 Figure 1 is a view of the tool as seen in side elevation.

Figure 2 is a view in vertical longitudinal section.

Figure 3 is a sectional view of the tool as 65 seen on the line 3-3 of Figure 2 with the expander removed.

Figure 4 is a view in section and plan as seen on the line 3-3 of Figure 2 with the 70 washer removed.

Figure 5 is a plan view of the retaining washer.

Figure 6 is a detail vertical section of the blade supporting block.

Figures 7 and 8 are plan views showing 75 modified forms of arrangement of the cutting blades.

Figure 9 is a perspective view of one of the adjustable blades.

More specifically, 10 indicates a shank 80 member which is here shown as comprising a stem 11 encompassed by a sleeve 12 and fitted with a handle 13. An intermediate portion of the stem or shank is provided with screw threads 14 and is formed with 85 an enlarged cylindrical part 15 providing a centering guide for an expander or sleeve member 16, the lower end of the bore of which sleeve member is larger in diameter than the threads 14 to slip over the threads 90 and slidably fit the part 15. The bore of the sleeve is threaded above the lower portion thereof to screw on the threads 14. Below the cylindrical part 15 of the shank there is provided a threaded plug 17, which 95 screws into and through a threaded bore 18 extending through the lower end of a block 19. The lower end face of the plug 17 is provided with a conical centering seat 20, and has a threaded socket to receive a 100 threaded end 21 of an interchangeable pilot stem 22.

Below the threaded end 21 on the pilot stem is formed a conical shoulder 23 the counterpart of the conical seat 20 so that 105 when the shoulder is seated the stem will be precisely axially arranged with respect to the shank 10.

The stem 22 forms one of a series each of 110 which is of different diameter for the obvious purpose of adapting the tool to be properly centered when grinding valve faces of

different valve organizations; the stems 22 being applicable to respective stem guide apertures for the valve stem.

The body 24 of the block 19 is annular in outline, has a flat top face and a tapered bottom face, and depending therefrom is a hub 25 through which extends the bore 18 and in which the plug 17 is screwed. The block 19 is provided with a bore 26 of larger diameter than the bore 18, extending upwardly through the body 24 and through a collar 27 extending upwardly from the top of said body. The body is provided with a series of guide slots 28 extending through 15 the upper face thereof and also extending from the bore 26 outwardly through the block, so that a series of cutters or blades 29 may be readily inserted into the outer end of the guide slots 28 and removed therefrom. 20 The slots 28 may be diametrically opposed as shown in Figure 3 or may be arranged to the side of the diametrical centers $a-a$ of the block 19 and of the shanks 10 and 22 as shown in Figure 7, so that the cutters will 25 be disposed in offset relation to the radii struck from the axis of rotation of the tool; or they may be offset diametrically in relation to each other, as shown in Figure 8.

The cutters 29 are slightly higher than the 30 depth of their respective slots 28 through the body 24, so that they extend above the flat top face of the body 10 and are therefore, designed to be severally engaged by a retaining washer 30. The retaining washer 35 30 is preferably of thin and flexible material and is designed to be pressed firmly down on the upper or top edges of the inserted cutters by means of a clamp nut or annulus 31 which is screwed on the collar 27, and 40 which clamp nut may have a polygonal exterior surface to facilitate the locking of the ring or washer 30 when the nut 31 is screwed down on the threaded collar 27.

The upper edges of the cutters 29 are 45 formed with side flanges 32 which seat on the top face of the block and support the cutters against tipping movement in any direction and also afford a wide surface for the clamping nut to bear upon. The outer or 50 blade ends of the cutters are formed on an incline, as indicated at 33 in Figure 9, to correspond with the taper of the valve seat to be faced; and are designed to project a short distance beyond the tapered lower face of 55 the carrier block.

The slots 28 extend through the collar 27 and in order to prevent the rotation of the washer 30 the latter may have one or more inwardly extending locking lugs 34 to extend into the portion of the slots 28 in the collar 27.

When the several cutters have been arranged in their respective slots in the body block or member 19 the clamp washer can be 60 forced downwardly at first with light pres-

sure by the clamp nut so as to hold the cutters against ready dislodgment. Then the expander sleeve 16 which has a lower exterior conical end 35 is advanced down the screw threads 14 until it engages beveled upper inner corners 36 formed on the cutters 29, with the result that the cutters will be uniformly moved outwardly by the action of the conical surface 35 thereon. 70

When the cutters have been adjusted outwardly or inwardly to the desired degree the clamp nut is then set up tight against the washer and this locks the cutters securely in place, with the flanges 32 seating on the block and clamped thereon beneath the washer, the 80 sides of the cutters abutting against the sides of the slots and the inner ends abutting against the expanding sleeve. The cutters will thus be securely held against displacement. To prevent play of the lower and 85 acting end of the expander 16 its inner surface is preferably turned cylindrical to closely fit on the guide portion 15 of the stem 11 and the stem is formed with an annular channel 36 beneath the portion 15 into which 90 the inner ends of the cutters may extend when in a fully retracted position. 90

In the operation of the tool, a shank 22 is placed thereon according to the size of the valve stem guide opening of the valve 95 seat to be faced and is inserted in the opening to center the tool and hold it relative to the valve seat. The cutters are then adjusted to conform to the valve seat and the tool is oscillated through the shank in the 100 manner common to tools of this character, so as to cause the edges of the inclined faces of the cutters to scrape the inclined face of the valve seat.

While I have shown and described a specific embodiment of my invention I do not 105 limit myself to the exact construction and arrangement shown, but may make such changes as may come within the scope of the appended claims; for example, any desired number of cutters may be used, and 110 in some instances the locking washer may be dispensed with.

In a co-pending application filed February 3, 1920, Serial No. 356,065, I have set 115 forth a tool similar to the one disclosed herein, which application embodies broad claims based on the slidably mounted cutters arranged in open ended slots with means for uniformly advancing the cutters, 120 and I therefore do not claim in this case any invention except those specifically set forth in claims hereof.

I claim:

1. A valve seat facer including a block, 125 a shank secured in said block, a screw thread and a cylindrical part on said shank, the cylindrical part being below said screw thread, a sleeve having an internal thread to fit the thread on said shank and the bore 130

of the sleeve below the internal thread being larger in diameter than the thread to fit closely on said cylindrical part, said block being provided with a plurality of outwardly extending slots, and cutters in said slots, the inner upper corners of said cutters being beveled, the lower end of said sleeve being conical to engage the beveled corners of said cutters to force the cutters outwardly 5 on advancing the sleeve on the screwthreads, said cutter having side flanges on their upper edges seating on the upper face of said block, and means screwed on the block for clamping the flanges of the cutters against 10 the block.

2. In a tool for facing valve seats, a block formed with a central bore and having slots leading outwardly from said bore and opening at the periphery of the block, cutters 20 slidably arranged in said slots having inclined outer end faces projecting beyond the edge of the block, side flanges on said cutters seating on the top face of the block, a shank extending into the bore of the block 25 having a threaded portion, a sleeve screwed on said shank having a tapered end adapted to bear against the inner ends of the cutters, a clamping nut encircling said sleeve and screwed on the block adapted to clamp the flanges of the cutters against 30 the block.

3. In a tool for facing valve seats, a block formed with a central bore and having slots leading outwardly from said bore and opening at the periphery of the block, cutters 35 slidably arranged in said slots having inclined outer end faces projecting beyond the edge of the block, side flanges on said

cutters seating on the top face of the block, a shank extending into the bore of the block having a threaded portion, a sleeve 40 screwed on said shank having a tapered end adapted to bear against the inner ends of the cutters, a clamping nut encircling said sleeve and screwed on the block adapted to clamp the flanges of the cutters against the 45 block, a washer interposed between the clamping nut and the cutters, and means for holding the washer against turning on the block.

4. In a valve seat facer, a body block 50 formed with open ended slots, cutters slidably mounted in said slots having side flanges on their upper edges seating on the upper face of said block, and means for clamping the flanges of the cutters against 55 the block.

5. In a valve seat facer, a body block 55 formed with open ended slots, cutters slidably mounted in said slots having side flanges on their upper edges seating on the 60 upper face of said block, and means screwed on the block for clamping the flanges of the cutters against the block.

6. In a tool for facing valve seats, a block having slots leading outwardly and 65 opening at the periphery of the block, cutters slidably arranged in said slots, side flanges on said cutters seating on the top face of the block, an externally threaded collar on said block, and a clamping nut 70 screwed on said collar, adapted to clamp the flanges of the cutters against the block.

EUGENE O. MYERS.
